UNITED STATES PATENT OFFICE

159,357

DRESS

Abraham Lipshitz, Flushing, N. Y.

Application January 27, 1950, Serial No. 7,527

Term of patent 3½ years

(Cl. D3—26)

To all whom it may concern:

Be it known that I, Abraham Lipshitz, a citizen of the United States, residing at 75-07 175th Street, Flushing, L. I., New York, have invented a new, original, and ornamental Design for a Dress, of which the following is a specification, reference being had to the accompanying drawing, constituting a part hereof:

Fig. 1 is a front view of a dress showing my new design.

Fig. 2 is a rear view.

I claim:

The ornamental design for a dress, substantially as shown.

ABRAHAM LIPSHITZ.
